METHOD OF AND MEANS FOR TELEVISION
TRANSMISSIONHanns-Heinz Wolff, Berlin, Germany, assignor, by
mesne assignments, to Loewe Radio, Inc., a cor-
poration of New YorkApplication December 4, 1936, Serial No. 114,161
In Germany December 10, 1935

9 Claims. (Cl. 178—7.2)

The invention relates to a method of and means for television transmission, making use of cathode ray tubes, in which a storage of light-electric excitations and the initiation of current impulses corresponding to the stored excitations by cathode ray scanning or the like take place. Arrangements of this nature have been developed according to the point of view of raising, by way of storage, the image-content impulses employed for transmission purposes to sufficiently large amplitudes.

In the method according to the invention the light-electric excitation and the discharge scanning, for the sake of definite charging and discharging conditions, occur at different times in respect of each element of the picture-receiving plate. Each individual element is accordingly illuminated for a certain period and is struck by the scanning ray after the exposure has been completed.

The invention is based on the idea that if too great a length of time elapses between illuminating and scanning, the "electric image" on the light-electric plate varies owing to mutual influence of the different charged image elements, especially in the sense of softening of contrast. This will occur even in those cases in which by very careful insulation a compensation of the charge by surface leakage currents is to a large extent suppressed. A compensation of the charge is caused in part by capacitative effect of the different image elements one upon another, and in part by the reactionary effects of space charges, which form in front of the image elements, are determined, as regards their strength and spacial extent in the first place by the individual charges, and which have the tendency to compensate each other and then by way of a reactionary effect alter the "electrical image."

According to the invention, therefore, care is taken that the interval of time between completion of the illumination of an individual image element and its scanning by the cathode ray has practically the same value in respect of all image elements. Care is preferably also taken that this interval of time is as short as possible. Additional features of the invention are set forth in the following description and explanation in conjunction with the accompanying drawing. Of the drawing

Fig. 1 shows diagrammatically the parts of the total arrangement essential for a form of embodiment of the invention, whilst in

Figs. 2 and 5a-c is shown the image area or

image field for illustrating certain considerations important for the invention, in

Fig. 3 a diaphragm arrangement not in accordance with the invention, and in each of

Figs. 4 and 6 a diaphragm arrangement according to the invention.

The intermittent uncovering and interruption of the passage of the ray from the object to be transmitted, or a part thereof, to the light-electrically sensitive plate, or a corresponding part thereof, may be performed by means of a rotating diaphragm. The opening or openings in this diaphragm which uncover or partially uncover the passage of the ray must appear sharply on the light-electrically sensitive plate simultaneously with the object of reproduction. The diaphragm should accordingly be arranged if possible either immediately in front of the light-electrically sensitive plate or immediately in front of the object of reproduction. The former arrangement is only possible if the light-sensitive plate is situated sufficiently near the wall of the cathode ray tube. The latter arrangement can be performed only in the case of image or film transmissions, and then only with difficulty. In very many cases it will not be possible to fulfill either of these two requirements. According, therefore, to an additional feature of the invention the procedure will be such that the object of reproduction is first reproduced sharply on the diaphragm, and then the diaphragm together with the real image of the object of reproduction reproduced sharply on the light-sensitive plate. The diagram of this arrangement is shown in Fig. 1. In the same, 1 is the object to be reproduced, 2 the cathode ray tube with the light-sensitive plate 3, 4 the diaphragm having the axis of rotation 5, 6 a reproducing lens, which projects an image 7 of the object 1 on to the diaphragm 4, and 8 a second reproducing lens which reproduces the image 7, so far as it is uncovered by the diaphragm, on the plate 3 at 7'.

In Fig. 2 the image 7 (7') is shown as being divided into m lines each having n image elements, i. e., altogether into $m \cdot n$ image elements ($a_{11}, a_{12}, \dots, a_{mn}$), which for the sake of simplicity are assumed to be square. The arrow 9 represents the direction in which the lines of the image 7' are scanned by the cathode ray. The rotating diaphragm arrangement operates in accordance with Fig. 3, in such fashion that a shading edge 10 of a diaphragm aperture passes over the image 7 in the same direction in which the line scanning of the image 7' is effected. Be t_1 the moment at which the image elements of the

first column are again shaded after being illuminated, and be $t_2 = t_1 + \Delta t$ the time at which the cathode ray starts scanning the image area $7'$ at the point a_{11} . The difference in time between shading and scanning accordingly amounts, for the image point a_{11} , to Δt . The point a_{11} is shaded at the same moment as the point a_{11} , but is scanned by the cathode ray by the amount

$$10 \quad \frac{t_b(m-1)n \text{ sec}}{m \cdot n} = t_b \frac{m-1}{m} \approx t_b \text{ sec.}$$

later than the point a_{11} , assuming that t_b represents the image-scanning period in seconds.

The arrangement in Fig. 3 accordingly shows disadvantages which are to be obviated by the method according to the invention, as in this arrangement there is no use in providing Δt with a value which is small in relation to the image scanning period t_b . An arrangement according to the invention is shown in Fig. 4. In this figure the arrangement is such that a shading edge 10 of a diaphragm aperture moves over the image 7 in such fashion that it runs parallel to the lines along which the cathode ray scanning takes place that the movement of said edge occurs perpendicularly to the direction of the lines in the sense of the sequence in which the lines are scanned by the cathode ray. In this arrangement the greatest difference between the time intervals between the shading and the cathode ray scanning of the individual image elements is evidently approximately equal to one line period, which in many cases may already represent a sufficient degree of conformity.

35 In this connection the arrangement should be such that the edge 10 of the diaphragm aperture passes over the image 7 within the same period which is required by the cathode ray for scanning the image 7'. If the cathode ray has scanned the entire image, the line $a_{11} \dots a_{mn}$ must in the meantime have been illuminated anew and already again shaded before the cathode ray starts the next scan. It follows that the diaphragm 4 requires to be furnished with a rim of evenly distributed apertures 11. The dimensions and the distribution of these apertures are determined by the following points of view:

40 In the case of film transmission with intermittent advance of the film there must be provided between two apertures an intermediate space of such nature that the entire image field is shaded during a certain fraction, necessary for the advance of the film, of the complete operating period t_g . Be this fraction assumed to 45 amount, for example, to $\frac{1}{4}t_g$. It would be desirable in itself for the cathode ray to start the next scan (at the point a_{11}) practically immediately after scanning the element a_{mn} . This, however, is not feasible. To enable the ray to 50 start the new scan upon its arrival at the lower edge of the image it would be necessary, when it reaches the lower edge of the image, for a shading of the entire image field during the time interval

$$65 \quad \frac{t_g}{4}$$

60 and an illumination and renewed shading of the first line to have already taken place. The complete shading would accordingly require to commence at a time when the cathode ray is situated at a distance from the lower edge of the image which corresponds with the period of time

$$70 \quad \frac{t_g}{4} + t_1 + \Delta t$$

if t_1 is assumed to be the duration of illumination as determined by the width of the diaphragm aperture. The ray scanning, however, would then require to lag behind the darkening to the extent of

$$75 \quad \frac{t_g}{4} + \Delta t + t_1$$

i. e., there would result the contradiction

$$10 \quad \Delta t = \frac{t_g}{4} + t_1 + \Delta t$$

The ray scanning accordingly requires to be interrupted for the duration

$$15 \quad \frac{t_g}{4} + t_1$$

i. e., in the assumed case that the time

$$20 \quad \frac{t_g}{4}$$

is required for the advance of the film, of the time available for one scan the time interval

$$25 \quad \frac{t_g}{4}$$

is lost. For the sake, therefore, of the smallest possible loss of time available for cathode ray scanning, the width of the slot will as far as possible, be selected to be so small that t_1 may be disregarded in relation to

$$30 \quad \frac{t_g}{4}$$

so that a loss of time available for the cathode ray scanning is occasioned practically by the advance of the film alone.

An additional reason for making the width of the slot as small as possible consists in the fact that if the slot is too wide, the charges of an image element undergo already during the illumination detrimental variations such as the invention seeks to avoid. It is reasonable to select t_1 and Δt to be of the same order.

The last aspect referred to is also decisive in the direct transmission of moving occurrences, in which the loss of time by advance of a film

$$40 \quad \frac{t_g}{4}$$

is not involved.

The ratio between the mutual distance of two neighbouring slots and the width of a slot amounts to

$$55 \quad \frac{t_g - t_1}{t_1}$$

If the disc 4 possesses s slots 11 distributed about its periphery, the same, according to a further feature of the invention, must have a circumferential velocity which is equal to

$$60 \quad \frac{1}{s}$$

times the number of image changes per second, i. e., for example in the case of 25 image changes per second and 25 slots

$$65 \quad 1 \frac{\text{revolution}}{\text{second}}$$

In the case of rapidly moving occurrences which are directly transmitted the arrangement according to the invention has a further important advantage, which will be explained with reference to Figs. 5a-c. Be a bright rod assumed to move over the image field 1 (7) on a dark ground, e. g., during a complete image scanning period from

the position 12 into the position 13 according to Fig. 5a. Upon omission of the above described diaphragm or analogous means this results in an image of the form of the triangle 14 (see Fig. 5b), since until the scanning cathode ray has reached, for example, the line of the image indicated by the broken line, all image elements of this line situated within the area 14 have received light excitations corresponding to the light intensity of the rod. If on the other hand only one or a few lines are illuminated at a time, and that shortly before they are scanned by the cathode ray, there results as image substantially the confinement 15 of the triangle 14. A moved image of this nature, therefore, however appearing distorted according to Fig. 5c, does not appear in blurred form as shown in Fig. 5b. It is evident that the distortion represents a considerably less serious drawback than the blur.

The advantages to be obtained by the invention are achieved to a still greater extent than in the arrangement described above by the following arrangement.

The diaphragm 4 is constructed as a spiral aperture disc on the lines of the Nipkow disc (see Fig. 6). The apertures are made in the form of longer or shorter slots or in the extreme case as openings each uncovering only one image element at a time, dependent on the extent to which it is desired to make use of the storage effect or on whether it is desired to dispense with the same for the sake of a more complete elimination of the disturbances which the invention is intended to reduce. The width of the slots is adapted to the width of the scanning lines and their number is selected to be equal to the number of lines. The circumferential velocity of the disc per second is in this case equal to the complete number of image scannings per second.

In order still further to eliminate even the distortion described in conjunction with Figs. 5a-c there may be employed in accordance with the invention a simple or preferably multiple interlaced line method, the number of image scannings per second being doubled or preferably tripled, generally multiplied with corresponding reduction of the number of lines per image scanning operation. According to a subsidiary feature of the invention the diaphragm 4 is then given a form which corresponds to that of the scanning discs of television transmitters operating according to the interlaced scanning method (compare for example the applications Ser. No. 36008/35 filed Aug. 13, 1935), attention being merely called to the fact that the openings may again have the form of slots extended in the direction of the lines for the purpose of obtaining a certain storage effect. In this form, therefore, the arrangement according to the invention combines the following important advantages:

(1) Variations in charge are avoided by a particular selection of the duration of illumination and the chronological order of illumination and scanning.

(2) Blurring effects in the transmission of rapidly moving occurrences are avoided by brevity of the illumination of the individual image element, and

(3) Distortions in the transmission of rapidly moving occurrences are avoided by the use of a, preferably multiple, interlaced line method.

I claim:

1. In a television transmitter comprising a cathode ray tube having a photo-electric mosaic upon which the image to be transmitted is pro-

jected and which is scanned by a cathode ray, means to illuminate each element of said mosaic only for a small part of an image change period and to scan it immediately thereafter, said means consisting of an obturating diaphragm rotating synchronously with the scanning, said diaphragm having a plurality of elongated apertures being so arranged as to uncover at once at least one of the image lines. 5

2. In a television transmitter comprising a cathode ray tube having a photo-electric mosaic upon which the image to be transmitted is projected and which is scanned by a cathode ray, means to illuminate each element of said mosaic only for a small part of an image change period 15 and to scan it immediately thereafter, said means consisting of an obturating diaphragm rotating synchronously with the scanning, said diaphragm having a spiral of apertures similar to a Nipkow disc. 20

3. In a television transmitter comprising a cathode ray tube having a photo-electric mosaic upon which the image to be transmitted is projected and which is scanned by a cathode ray, means to illuminate each element of said mosaic only for a small part of an image change period 25 and to scan it immediately thereafter, said means consisting of an obturating diaphragm rotating synchronously with the scanning, said diaphragm having a spiral of apertures similar to 30 a Nipkow disc for interlaced scanning.

4. In a television transmitting device comprising a two-dimensional photo-electric mosaic screen in combination means for performing a lighting operation to illuminate said mosaic screen from the object to be transmitted, interrupting means for periodically interrupting the lighting of each element of said mosaic screen, the lighting period allowed by said interrupting means being smaller than an image change period, scanning means for performing a scanning operation to scan said mosaic screen by a ray, and means for establishing a co-operative relation between said interrupting and said scanning means such as to cause said lighting and said 40 scanning operation to act substantially simultaneously on, though at each moment on different parts of, said mosaic screen and such as to admit the passing of at most a small time interval between the end of said lighting operation 45 and the beginning of said scanning operation for each element of said mosaic screen. 50

5. In a television transmitting device comprising a two-dimensional photo-electric mosaic screen in combination means for performing a lighting operation to illuminate said mosaic screen from the object to be transmitted, interrupting means comprising a rotating apertured diaphragm disposed between the place of said object to be transmitted and said mosaic screen 60 for periodically interrupting the lighting of each element of said mosaic screen, the lighting period allowed by said interrupting means being smaller than an image change period, scanning means for performing a scanning operation to scan said 65 mosaic screen by a ray, and means for establishing a co-operative relation between said interrupting and said scanning means such as to cause said lighting and said scanning operation 70 to act substantially simultaneously on, though at each moment on different parts of, said mosaic screen and such as to admit the passing of at most a small time interval between the end of said lighting operation and the beginning of said 75

scanning operation for each element of said mosaic screen.

6. In a television transmitting device comprising a two-dimensional photo-electric mosaic screen in combination means for performing a lighting operation to illuminate said mosaic screen from the object to be transmitted, interrupting means comprising a rotated apertured diaphragm disposed between the place of said object to be transmitted and said mosaic screen for periodically interrupting the lighting of each element of said mosaic screen, the lighting period allowed by said interrupting means being smaller than an image change period, scanning means for performing a scanning operation to scan said mosaic screen by a ray, optical means for producing in the plane of said diaphragm a real image of said object to be transmitted, further optical means for producing on said screen an image of any aperture of said diaphragm which, in the movement of said diaphragm, happens to be situated in the path of the light projected from the mentioned object onto said screen, and means for establishing a co-operative relation between said interrupting and said scanning means such as to cause said lighting and said scanning operation to act substantially simultaneously on, though at each moment on different parts of, said mosaic screen and such as to admit the passing of at most a small time interval between the end of said lighting operation and the beginning of said scanning operation for each element of said mosaic screen.
7. The invention set forth in claim 5, wherein said rotating diaphragm is provided with a plurality of elongated apertures, wherein the main extent of any aperture which, in the rotation of said diaphragm, happens to be situated in the path of the light projected from the mentioned object onto said screen, is parallel to the lines

along which said screen is scanned, and wherein means are provided for rotating said diaphragm in that sense, with which the lighting ray passing through said apertures moves across said screen in the same direction in which the lines of the ray scanning follow one on the other.

8. The invention set forth in claim 5, wherein said rotating diaphragm is provided with a plurality of apertures which have, similarly to the holes of a Nipkow disc, a spiral distribution over said diaphragm.

9. In a television transmitting device comprising apparatus for intermittently advancing a cinematographic film and a two-dimensional photo-electric mosaic screen in combination means for performing a lighting operation to illuminate said mosaic screen from said film, interrupting means comprising a rotated apertured diaphragm disposed between the place of the film-picture to be transmitted and said mosaic screen for periodically interrupting the lighting of each element of said mosaic screen, the lighting period allowed by said interrupting means being smaller than an image change period, scanning means for performing a scanning operation to scan said mosaic screen by a ray, means for blocking said ray during a time interval which is the sum of the time required for one advancing movement of the film and of said lighting period, and means for establishing a co-operative relation between said interrupting and said scanning means such as to cause said lighting and said scanning operation to act substantially simultaneously on, though at each moment on different parts of, said mosaic screen and such as to admit the passing of at most a small time interval between the end of said lighting operation and the beginning of said scanning operation for each element of said mosaic screen.

HANNS-HEINZ WOLFF. 40
